US00D580852S

(12) **United States Design Patent**
Heinzen et al.

(10) **Patent No.:** US D580,852 S
(45) **Date of Patent:** ** Nov. 18, 2008

(54) **BATTERY FOR A COMBUSTION TOOL**

(75) Inventors: **William J. Heinzen**, Glenview, IL (US);
Robert L. Turk, Waukegan, IL (US);
Robert Meyer, Palatine, IL (US)

(73) Assignee: **Illinois Tool Works Inc.**, Glenview, IL (US)

(**) Term: **14 Years**

(21) Appl. No.: **29/298,652**

(22) Filed: **Dec. 10, 2007**

(51) **LOC (8) Cl.** 13-02

(52) **U.S. Cl.** D13/103

(58) **Field of Classification Search** D13/102-106,
D13/110, 118-119, 184; 429/96-100, 163,
429/176

See application file for complete search history.

(57) **CLAIM**

The ornamental design for a battery for a combustion tool, as shown and described.

DESCRIPTION

FIG. 1 is a top perspective view of the battery of the present invention;

FIG. 2 is a front view of a battery of FIG. 1;

FIG. 3 is a right side view of the battery of FIG. 1;

FIG. 4 is a left side view of the same;

FIG. 5 is a rear view of the battery of FIG. 1;

FIG. 6 is top view of the same; and,

FIG. 7 is a bottom view of the battery of FIG. 1.

The structure depicted in broken lines is provided for environment purposes only and does not constitute part of the claimed invention.
